CLAIM

The ornamental design for a toy vehicle, as shown and described.

DESCRIPTION

FIG. 1 is a front perspective view of a toy vehicle taken from the right side showing my new design;

FIG. 2 is a front perspective view of the toy vehicle in FIG. 1 taken from the left side;

FIG. 3 is a right rear perspective view thereof, the left side opposite being a mirror image thereof to the side shown; and,

FIG. 4 is a top plan view thereof.

FIG. 2

FIG. 1
